(57) **CLAIM**

We claim the ornamental design for a portable telephone, as shown and described.

DESCRIPTION

FIG. 1 is a perspective view of a portable telephone, when closed, according to our new design;
 FIG. 2 is a front view thereof, when closed;
 FIG. 3 is a rear view thereof, when closed;
 FIG. 4 is a top view thereof, when closed;
 FIG. 5 is a bottom view thereof, when closed;
 FIG. 6 is a left side view thereof, when closed;
 FIG. 7 is a right side view thereof, when closed;
 FIG. 8 is a front view thereof, when open and with parts rotated relative to each other; and,
 FIG. 9 is a right side view thereof, when open.
